RAZOR BLADE SHARPENER

David Heller, Brooklyn, N. Y.

Application October 19, 1943, Serial No. 506,833

5 Claims. (Cl. 51—161)

This invention relates to devices for sharpening safety-razor blades. More particularly my invention is directed toward providing a highly improved construction for a device for sharpening safety-razor blades, preferably of the double-edge type, by the use of a hollow cylindrical member of glass or other suitable material.

One of the objects of my invention is to provide a safety-razor blade sharpener of the class described, in which a plurality of safety-razor blades, such as, for example, a week's supply of blades, may be simultaneously sharpened and left in position in the device until used, which is further characterized by the fact that the blades are maintained in effective position for sharpening by the inherent flexibility of the blades themselves.

Another object of my invention is to provide a safety-razor blade sharpener of the class described which will comprise relatively few and simple parts, which shall be easy to assemble and relatively inexpensive to manufacture and which, at the same time, shall represent a general improvement in the art.

Still other objects and advantages of my invention will become apparent in the following detailed description thereof.

In the accompanying drawing,

Fig. 1 is a vertical sectional view of a safety-razor blade sharpener constructed and arranged in accordance with my invention;

Fig. 2 is a top plan view thereof;

Fig. 3 is a cross-sectional view taken substantially along the line 3—3 of Fig. 1;

Fig. 4 is an elevational view of the device shown in Fig. 1, but with a portion of the outer wall broken way to disclose the interior construction thereof and illustrating the manner of its use; and

Fig. 5 is a perspective view of one of the parts of the device shown in Figs. 1, 2 and 4, removed and apart therefrom.

Referring now in detail to the drawing I have shown a safety-razor blade sharpener constructed and arranged in accordance with my invention and comprising a hollow cylindrical member 10, preferably of glass, but which may be made of any other suitable material. It is noted that the surrounding wall 10a of the member 10 is tapered so that it is of larger diameter at the top than at the bottom. Into the hollow of the member 10, I place a carrier member 11, having a flange 11a at the bottom thereof adapted to rest upon the bottom 10b of the member 10. It is noted that the outer diameter of the flange 11a

is less than the inside diameter of the adjacent surrounding wall 10a, so that the said carrier member 11 may be freely axially rotated within the container and, at certain times, freely slidably withdrawn therefrom. At certain circumferentially spaced points the carrier member 11 is provided with vertically disposed channels 12 of any desired cross-sectional contour and extending inwardly from the outer surface 11b of the carrier member 11 for a predetermined distance. Into each of the channels 12 there is freely slidably received a longitudinal block 13 of similar cross-sectional contour to that of the said channels 12 so that the blocks 13 will be restricted in lateral displacement within the channels 12.

In Fig. 5 of the drawing I have shown a detailed perspective view of one of the blocks 13 completely removed from the carrier member 11. It is noted that on the face 13a of the block adjacent the wall 10a of the member 10, there is provided a raised ridge 14 of predetermined length, width and height, and designed to be received within the longitudinal slot of any standard type double-edged safety-razor blade; such as, for example, the blade 15 shown in Fig. 4 of the drawing which has the usual slot 15a.

In assembling the device for use, each block 13 may be withdrawn from its channel 12, as shown by the dot and dash line 13' in Fig. 4, and a blade 15, which it is desired to sharpen, is mounted on the block 13, by having the ridge 14 project through the slot 15a. The block 13 is then slidably replaced in its channel 12, as clearly shown in Fig. 4 of the drawing. The front-to-back dimension of each block 13 is such that, when a blade 15 is mounted thereon and received within the hollow of the member 10, the said blade 15 will be caused to flex slightly so as to resiliently press against the surface of the member 10. It is noted that, due to the fact that the blocks are substantially diametrically arranged, the carrier member 11 may be resiliently maintained within the hollow of the member 10, solely by and because of the flexing of the blades 15 as above described.

By the above described construction it is seen that the blades 15 will resiliently adjust themselves so that there is no undue pressure put on any one of them and in that way a more even sharpening effect may be obtained.

When it is desired to sharpen the blades 15 it is merely necessary to oscillate the carrier member axially a number of times and any selected block 13 slidably withdrawn and the blade 15 removed therefrom for use. If desired, after the

blades have been sharpened as above described the blocks 13 may be removed and the blades 15 thereon reversed so that opposite sides of the cutting edges may be sharpened instead of only one side.

It is also noted from the above described construction and operation of my device that the blocks 13 may be longitudinally reciprocated to sharpen the cutting edges of the blades 15 in a longitudinal direction in addition to the sharpening in a transverse direction caused by the axial rotation of the carrier member 11. Thus a much finer cutting edge is obtained on the blade.

To facilitate the withdrawal and insertion of the blocks 13, each block may be provided with a gripping knob 16 of any well known design. It is also noted that the surface 13a of each block may be tapered to correspond to the taper of the wall 10a of the member 10.

To facilitate the axial rotational oscillatory movement of the member 11 used to sharpen the blades, the said member 11 may be provided with an upwardly projecting finger gripping portion 16 of reduced diameter, as clearly shown in the drawing.

If it is desired to provide a safeguard against the undesired withdrawal or falling out of the carrier member 11, such as, for example, when all of the blocks are removed therefrom, I may provide the following construction:

On the inner surface of the wall 10a of the member 10, I provide a circumferential groove 17 designed to receive therein a resiliently expanding ring 18 of any well known type suitable. The groove 17 and ring 18 are disposed slightly above the flange 11a and thus hold the member 11 in place. To remove the member 11 for any desired reason it is merely necessary to exert a pulling force sufficient to overcome the resilience of the ring 18 so that it may be pulled out of the groove 17.

In accordance with the above described construction and operation, my invention is adapted so that I may provide seven blocks 13, to provide one razor for each day in the week and so that the user will not become confused and repeatedly take the same razor. To this end I mark on the carrier member 11 suitable indicia adjacent each block 13 to designate the days of the week, as clearly shown in Fig. 2 of the drawing.

I have found that good results are obtained when the carrier member 11 and the blocks 13 are made of wood or plastic, but they may be made of any other desired suitable material.

While I have described the preferred construction and operation of a razor-blade-sharpening device under this invention, I am aware that numerous changes may be effected without departing from the spirit of my invention and I therefore do not wish to be understood as limiting the scope of my claims by the positive terms employed in connection with the description.

Having described my invention, what I claim and desire to secure by Letters Patent is:

1. In a blade sharpener of the character described, a hollow cylindrical member, a carrier member received within said hollow member and

axially relatively rotatable with respect to said hollow member, means for supporting a plurality of razor blades on said carrier member in circumferentially spaced relationship and in such manner that the said blades will be caused to flex into frictional contact with the adjacent wall of the hollow member, said last named means comprising an independent block for each blade, said blocks being mounted on said carrier member for rotational movement therewith, said blocks being additionally slidably movable with respect to said carrier member in a direction parallel to the axis of rotation of said carrier member so that a single blade may be selectively removed without necessitating the withdrawal of said carrier member from said cylinder member and without disturbing the remaining blades.

2. In a safety razor blade sharpener of the character described, the combination according to claim 1 in which each of said blocks is provided with a projection adapted to be received in a corresponding opening of a blade to prevent displacement of said blade during the sharpening process.

3. In a safety razor blade sharpener of the character described, a hollow cylindrical member, a cylindrical carrier member received within said hollow member, the outside diameter of said carrier member being less than the inside diameter of said hollow member to provide a free space therebetween, a plurality of circumferentially spaced channels extending inwardly from the side wall of said carrier member, said channels being of predetermined cross-sectional contour and disposed with their axes substantially parallel to the axis of said carrier member, a blade supporting block slidably received in each channel, each of said blocks being of such cross-sectional contour with respect to the said contour of said channels as to hold said blocks captive against lateral displacement in said channels and at the same time to permit axial sliding movement of said blocks with respect to said channels.

4. A safety razor blade sharpener according to claim 3 in which each of said blocks projects slightly beyond the side wall of said carrier member and into said free space, whereby the razor blades to be sharpened may be flexed between said blocks and the inner wall of said hollow cylindrical member, and means for holding a razor blade in effective sharpening position while said carrier member is axially rotated.

5. A safety razor blade sharpener according to claim 3 in which each of said blocks projects slightly beyond the side wall of said carrier member and into said free space, whereby the razor blades to be sharpened may be flexed between said blocks and the inner wall of said hollow cylindrical member, means on each of said blocks for holding a razor blade in effective sharpening position while said carrier member is axially rotated, and in which means are provided for limiting the outward axial movement of said carrier member with respect to said hollow cylinder during axial rotation thereof.

DAVID HELLER.
